REFRIGERATOR

Donald W. Sutherland, Sioux Falls, S. Dak., assignor to Servel, Inc., New York, N. Y., a corporation of Delaware

Application February 5, 1935, Serial No. 5,057
Renewed January 5, 1938

4 Claims. (Cl. 311—114)

My invention relates to refrigerators and more particularly to a rack or holder for use in a refrigerator cabinet.

It is an object of my invention to provide a rack or holder in which individual articles, such as eggs, automatically gravitate in sequence to a convenient point of removal as, for instance, just within a refrigerator door opening.

Another object is to provide a rack or holder 10 that may be removably suspended closely beneath a refrigerator shelf to increase storage capacity by utilizing the most likely available space of a loaded refrigerator.

A further object is to provide a rack or holder 15 on which an article may be conveniently grasped for removal.

My invention will be understood upon reference to the following description and the accompanying drawings of which:

20 Fig. 1 is a front view partly broken away of the upper part of a household refrigerator provided with a rack embodying my invention;

Fig. 2 is a perspective view of the forward end 25 of the rack;

Fig. 3 is a side elevation of the rack;

Fig. 4 is a section taken on line 4—4 in Fig. 3; and Fig. 5 is a top view of the rack.

Referring to Fig. 1, a refrigerator 10 provides a thermally insulated storage compartment 11 in 30 which is located a cooling element 12 of a suitable refrigeration apparatus. In the storage compartment 11 is a plurality of openwork shelves, usually constructed of bars or wire rods as shown. Beneath a shelf 13 is suspended a rack or holder 35 14 adapted to hold a series of generally similar articles and more particularly a series of generally spheroidal articles such as eggs. I prefer to suspend the rack 14 closely beneath the shelf 13 for the reason that space immediately beneath 40 a shelf is the most likely available space even in a fully loaded refrigerator. I also prefer to removably suspend the rack 14 so that its position in the refrigerator may be changed to take advantage of the space that is least likely to be 45 occupied or most likely to meet the desire of a user.

The structure of the rack 14 is more clearly shown in Figs. 2 to 5. In accordance with my invention, I provide a pair of substantially U-shaped suspension members 15 and 16. The upper ends of the member 15 are turned outwardly to form hooks 17 and the upper ends of the member 16 are turned outwardly to form hooks 18. The member 15 is of a slightly greater depth than 50 the member 16. The bottom portions of the

members 15 and 16 are flat and serve to support two pairs of parallel wire rods 19 and 20. The U-shaped suspension members 15 and 16 are arranged with their upper ends at the same level and are spaced apart so as to be adjacent opposite ends of the parallel wire rods 19 and 20. Since the members 15 and 16 are of different depths, the tracks formed by the wire rods 19 and 20 are inclined from the suspension member 16 downwardly in the direction of the suspension 10 member 15. The upper ends of the wire rods 19 are turned upwardly to form stops 23 and the lower ends are turned upwardly to form stops 21. The upper and lower ends of the wire rods 20 are likewise turned upwardly to form stops 15 24 and 22. A side rail 26 extends around the tracks 19 and 20 except at the forward end of the rack. The retaining ledge at the forward end of the rack is formed by the stops 21 and 22. A center spacing bar 25 affords further rigidity to 20 the rack intermediate the suspension members 15 and 16. The tracks 19 and 20, spacing bar 25, side rail 26, and the suspension members 15 and 16 may all be of tinned metal wires welded together as described.

The rack 14 may be suspended from the shelf 13, as shown, by engaging the hooks 17 and 18, at the upper ends of the suspension members 15 and 16, over shelf bars or rods 13a and 13b. The rack 14 is preferably suspended with the front, 30 that is, the lower end of the inclined tracks 19 and 20 adjacent the forward edge of the shelf 13 which may be just within the opening of the refrigerator door and in the forward part of the refrigerator storage compartment 11. The inclined tracks 21 and 22 are arranged as, for instance, by proper spacing of the wire rods to support a series of articles, especially articles which are generally spheroidal such as eggs. Eggs are prolate spheroids and are therefore placed on the 40 tracks 19 and 20 with their longer axes across the track as indicated in Fig. 2 so that the eggs tend to roll downwardly in sequence against the retaining ledge or stops 21 and 22. It will now be understood that an egg resting against one of 45 the stops 21 or 22 may be grasped at the top and bottom between fingers extending into the refrigerator storage compartment 11 and substantially horizontally between the stops 21 or 22 and also between the lower ends of the track 19 or 20. 50 It is, therefore, with ease that an egg or other article may be removed from the rack 14. It is also for this reason that the rack 14 may be suspended closely beneath the shelf 13 since no hand room is required between the rack and the shelf. 55

Eggs may be placed in the rack or holder 14 at the forward end of the rack by placing eggs one at a time on the lower end of the track 19 or 20, moving any egg or series of eggs that may already be on the track to the rear and away from the stops 21 or 22 to make room for the egg being added. When an egg is removed from the lower end of a track 19 or 20, any egg or series of eggs on the track above the egg being removed will 5 gravitate downwardly until restrained by the stops 21 or 22. Thus, as eggs are removed from the lower or front end of the rack, the remainder gravitate in sequence to the point of removal, wherefore an egg is always readily available at 10 a known and convenient point for removal from the refrigerator.

It will be understood that various changes may be made within the scope of my invention which is therefore not limited to that which is shown in 15 the drawings and described in the specification but only as indicated in the following claims:

What is claimed is:

1. In a refrigerator having a storage compartment and a shelf in said compartment, a rack for 20 supporting eggs and analogous rollable objects including a pair of substantially U-shaped suspension members, a track formed by a pair of parallel wire rods which rest upon and are secured to said members and which have unconnected up-turned ends at the front of the rack 25 constituting stops, said suspension members being of such relative depths as to support the track at an inclination from the rear toward the front of the compartment when said members are secured to and beneath said shelf.
2. An egg rack for use in refrigerator compartments consisting of a plurality of bars shaped to provide a basket like structure with the bottom thereof having a track or runway formed by 30

a pair of substantially parallel bars spaced to support eggs in a row, suspension members engaging beneath and secured to the track rods and adapted to suspend the rack from a refrigerator shelf with said track bars inclined toward the front of the rack so that eggs will gravitate forward as those in front are removed, and a stop adjacent to the front or lower end of the track. 35

3. A container for a refrigerator compartment, including a track for supporting eggs or like rollable objects in a row thereon, suspension members on said container for engagement with a shelf for supporting said container closely beneath said shelf with said track inclined toward the front of the compartment so that the eggs will gravitate forward as those in front are removed, and a stop adjacent the front or lower end of the track. 40

4. A container, for use in a refrigerator having a member therein with a substantially flat underside, said container having upstanding sides, and a bottom for retaining eggs within the same, said container including laterally spaced members constituting a track for supporting and 25 causing eggs to align themselves in a row thereon, means for supporting said track inclined toward the front of the refrigerator so that the eggs will gravitate down the track as removal is 30 made from the lower end of the track, stop means on the lower end of the track, said container being supported in said compartment beneath the flat underside of said member so that a top will 35 thereby be provided for the container capable of protecting eggs in the container during insertion of articles into and removal of articles from the refrigerator.

DONALD W. SUTHERLAND.
